UNITED STATES PATENT OFFICE.

JOSEPH T. HOMAN, OF CINCINNATI, OHIO.

DESIGN FOR A BACK FOR TOILET MIRRORS, BRUSHES, OR SIMILAR ARTICLES.

41,870.

Specification for Design.

Patented Oct. 31, 1911.

Application filed July 10, 1911. Serial No. 637,830. Term of patent 3½ years.

To all whom it may concern:

Be it known that I, JOSEPH T. HOMAN, a citizen of the United States, residing in Cincinnati, in the county of Hamilton and State of Ohio, have invented a new, original, and ornamental Design for Backs for Toilet Mirrors, Brushes, and Similar Articles, of which the following is a specification, reference being had to the accompanying drawing, forming part thereof.

The figure is a plan view of a toilet mirror, showing my new design.

I claim:

The ornamental design for a back for toilet mirrors, brushes, or similar articles, as shown.

JOSEPH T. HOMAN.

Witnesses:

CHARLES M. BODMER,
STANLEY BREWSTER.
